ALARM LOCK

Alde Lefebvre, New York, N. Y.

Application January 14, 1937, Serial No. 120,489

2 Claims. (Cl. 200—44)

This invention relates to alarm locks, an object of the invention being to provide a pin tumbler lock with improved circuit closing means so that when a key is positioned in the lock it will cause the movement of one or more pin tumblers to close the circuit and sound the alarm.

It is a well-known fact that many burglaries take place by the burglar having a proper key or a skeleton key to unlock a door or window, and it is the broad purpose of my invention to provide an alarm lock which when the proper key or any other key is positioned in the lock or an attempt made to position a key in the lock, an alarm will be sounded.

15 A further object is to provide improved circuit closing means which can be incorporated in the ordinary standard pin tumbler lock, and which will be comparatively simple in construction, efficient in operation, and strong and durable in use.

20 With these and other objects in view, the invention consists in certain novel features of construction and combinations and arrangements of parts, all of which will be more fully hereinafter described and pointed out in the claims.

25 In the accompanying drawing—

Fig. 1 is a view in longitudinal section through a pin tumbler lock equipped with my improved circuit closing means;

Fig. 2 is a view in transverse section on the line 2—2 of Fig. 1, and

Fig. 3 is a view similar to Fig. 2 illustrating a modification.

10 represents the casing, 11 the barrel, and 12 the pin tumblers with which locks of this character are ordinarily equipped. 13 indicates the springs on top of the pin tumblers held in the pin bores 14 by the ordinary covering plate 15, and 16 is the ordinary key to operate the lock.

Around the lock I secure a supporting clamp 17 securely held on the lock by means of a screw 18 and a nut 19. The screw 18 also functions as a terminal for the connection of a wire 20, which is grounded as shown at 21. In the clamp 17 a tubular member 22 of insulation is located, and 45 a washer 23, also of insulation, is clamped against the end of the tubular member 22 by means of a screw 24 and a nut 25. On this tubular member 22 an electric contact 26 is secured and projects above the lock casing, and a strip 27 of insulation is located between the contact 26 and the clamp 17 to prevent grounding of the circuit. This contact 26 is electrically connected to a wire 28 which in turn is connected to a battery or other source of electricity 29, the other side of the battery having a wire 30 connected thereto and

grounded as shown at 31. Included in the circuit with this wire 30, is a bell or other signal 32, and a manually operable switch 33 is located at any convenient point in the circuit.

In two of the bores 14 I provide circuit closing pins 34 which have heads 35 at their lower ends resting on the pin tumblers 12. These circuit closing pins extend through the plate 15 and through openings 36 in the covering plate 15 and through openings 37 in the clamp 17. The upper ends of these circuit closing pins 34 are normally spaced from the contact 26 but when the key 16 is positioned in the barrel of the lock it will cause the pin tumblers to be lifted and lift the circuit closing pins 34 to engage the contact 26 and close the circuit and sound the alarm. While I have illustrated two of these contact pins, it is to be understood, of course, that the invention is not limited to the particular number as I may employ one or more of these pins as desired.

The above described construction illustrated specifically in Figs. 1 and 2, is especially designed where the lock is to be used in a wooden door, but where the lock is to be used in a metal door, it is desirable to cushion the contact pins so as to prevent any possibility of the pins forcing the contact away from the lock to engage the metal door and short-circuit the alarm. This idea is illustrated in Fig. 3 of the drawing, where it will be noted that instead of providing the longer springs as illustrated in Figs. 1 and 2 of the drawing, I cut these springs in half and locate one short spring 38 directly on top of the pin tumblers 12 and enclose the same in a cup 39. The circuit closing pin 40, corresponding to the circuit closing pin 34 above described, has its headed end in the cup and against which the spring 38 operates. The other short spring 41 is located between the cup 39 and the covering plate 15. Thus it will be seen that the circuit closing pin 40 has a certain amount of cushioning in that it may move in the cup against the action of the spring and preventing any possibility of forcing the contact 26 against the metal of the door.

While I have illustrated and described what I believe to be preferred embodiments of my invention, it is obvious that various slight changes may be made with regard to the form and arrangement of parts without departing from my invention, and hence I do not limit myself to the precise details set forth but consider myself at liberty to make such changes and alterations as fairly fall within the spirit and scope of the claims.

I claim:

1. The combination with a pin tumbler lock, of
a circuit closing pin supported upon and movable
by a pin tumbler and projecting outside of the
lock, a split clamp around the lock, a screw and
5 nut coupling the end of the clamp, the screw
constituting an electric terminal, said circuit clos-
ing pin being in electric contact with the clamp
and a contact secured to the clamp and insulated
therefrom and located above the lock in position
10 to be engaged by the circuit closing pin when the
pin tumbler is elevated by the insertion of a key
in the barrel of the lock.

2. The combination with a pin tumbler lock, of
an inverted cup located in the tumbler bore of the
lock, springs in the cup and above the same re-
spectively, a circuit closing pin projecting through
the cup and projecting above the lock, a head on
said pin in the cup against which the lower spring
bears, and a contact insulated from the lock and
adapted to be engaged by said circuit closing pin
when a key is inserted in the lock.
